US00D878556S

(12) **United States Design Patent** (10) **Patent No.:** **US D878,556 S**
(45) **Date of Patent:** **** Mar. 17, 2020**

(54) **INJECTOR DEVICE**

(71) Applicant: **West Pharmaceutical Services, Inc.**, Exton, PA (US)
(72) Inventors: **Jason Williams Farris**, Gilbert, AZ (US); **Samuel Dauphinais**, Phoenix, AZ (US); **Brian Costello**, Whitehouse Station, NJ (US); **Raymond Protasiewicz**, Whippany, NJ (US)

(73) Assignee: **West Pharmaceutical Services, Inc.**, Exton, PA (US)

(**) Term: **15 Years**

(21) Appl. No.: **29/619,364**

(22) Filed: **Sep. 28, 2017**

Related U.S. Application Data

(63) Continuation-in-part of application No. 29/582,288, filed on Oct. 26, 2016, now Pat. No. Des. 806,234.

(51) **LOC (12) Cl.** **24-02**

(52) **U.S. Cl.**

USPC **D24/113**

(57) **CLAIM**

The design of an injector device, as shown and described.

DESCRIPTION

FIG. 1 is a top, front, right perspective view of an injector device of our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an exploded perspective view thereof.

The broken lines show portions of the design that form no part of the claimed design.

1 Claim, 8 Drawing Sheets

US D878,556 S
